UNITED STATES PATENT OFFICE.

REUBEN T. PALMER, JR., AND FREDERIC W. MERCER, OF NEW LONDON,
CONNECTICUT.

DEVICE FOR SUPPORTING AND STRETCHING BED-COMFORTABLES.

SPECIFICATION forming part of Letters Patent No. 604,414, dated May 24, 1898.

Application filed April 24, 1896. Renewed October 18, 1897. Serial No. 655,623. (No model.)

To all whom it may concern:

Be it known that we, REUBEN T. PALMER, Jr., and FREDERIC W. MERCER, citizens of the United States, and residents of the city 5 and county of New London, State of Connecticut, have invented certain new and useful Improvements in Devices for Supporting and Stretching Bed-Comfortables During the Operation of Quilting, which improvements 10 are fully set forth and described in the following specification, reference being had to the accompanying sheet of drawings.

The object of this invention is to provide a device of simple construction upon which a 15 bed-comfortable may be readily stretched and supported during the operation of quilting.

Said device, briefly described, consists of a framework bearing adjustable clamps that grasp the fabric at its sides and ends and 20 stretch and support the same while being quilted.

To assist in the explanation of our invention, the accompanying sheet of drawings has been provided, illustrating the same as 25 follows:

Figure 1 is a plan view of our device, showing the manner in which it operates to accomplish the end for which it is designed. Fig. 2 is an elevation of a portion thereof; and 30 Figs. 3, 4, and 5 are detail views of certain elements of our said device, Fig. 4 being an enlarged sectional view taken on line X X of Fig. 1.

Referring to the drawings, the letter *a* denotes a rectangular framework constructed, 35 preferably, of iron pipe and provided with legs or posts *b*², located at its corners or at points *c*.

To stretch the quilt upon the frame *a*, two 40 styles of clamps are preferably employed, serving, respectively, to hold the ends and sides of said quilt. Two of the first-named clamps are preferably employed to grasp the quilt at each end, said clamps consisting of a tube 45 that is slightly less in length than the width of frame *a*. Said tube is split longitudinally throughout its length, excepting for a short portion near each end, thus forming two semi-circular tube-sections, the shorter of which 50 is denoted by reference-letter *b* and is hinged at *d* to the companion section *b*'. Secured to

section *b*' are two or more studs *e*, that extend upward on the hinge side thereof and are threaded at their upper portions to receive correspondingly-threaded buttons *f*, 55 which latter may be swung or partially revolved to allow the clamp-section *b* to be raised or may be swung in the opposite direction to clamp said section *b* in its closed position, as will readily be understood by 60 reference to Fig. 3. The tension or "bite" of clamping-buttons *f* may be regulated by screwing said buttons upward and downward on studs *e*, the position of said buttons being largely determined by the thickness of 65 the fabric to be clamped by the device. The edge of said fabric is placed between sections *b* and *b*', the former section having been previously rocked back, so that the fabric may be entered, after which said section *b* is closed 70 and locked by means of the buttons *f*. To support the clamps *b*' upon frame *a*, certain blocks *g* are secured to said frame by means of bolts *h*, which blocks are provided with pockets *k*, one of said blocks being provided 75 to receive each end of the clamped section *b*'. Bolt *h* of each block *g* lies in a slot *a*², and thus means of adjustment is provided for the two clamps *b*, so that quilts of varying lengths may be accommodated. The second-named 80 clamps, provided to grasp and stretch the sides of the quilt, are also secured to frame *a* and several of such clamps are located at frequent intervals on opposite sides of said frame. Each clamp consists of a body portion *m* and a shank *n*, that is slotted, as at *n*', said body portion being substantially rectangular in plan view and through the same is cut an opening *m*', within which is hinged 85 a semi-oval jaw *o* by means of a pin *o*' and also an arm *p*, hinged therein on a pin *s*. Arm *p* enters a slot *o*² in jaw *o* and is provided with shoulders *p*' which, when said arm is rocked into a substantially vertical position, ride like a cam upon the periphery of 90 the semi-oval jaw *o* to bind the free end of the latter upon the body portion *m* of the clamp, and thus clamp the fabric *a*' between said free end and the body portion *m*. Slot *o*², near the hinged end of jaw *o*, is enlarged 100 sufficiently, as at *o*³, to permit the shoulders *p*' of arm *p* to pass therethrough after said

arm is rocked into the position shown in dotted lines of Fig. 5 to open the jaw. The shank *n* of the clamp is secured to frame *a* by means of a bolt *t*, said shank being entered 5 in a slot *a*³ in frame *a*. It will thus be seen that by reason of the means of adjustment thus provided the clamp may be readily regulated to accommodate quilts of varying widths.

10 When it is desired to utilize our device, the clamps *b*, *b'*, and *m* are first properly located on frame *a* to accommodate the fabric to be quilted, which latter is first secured in clamps *b* *b'*, as described, and then to the clamps *m*, 15 the two sets of clamps then serving to stretch and support the fabric in position for quilting.

Our invention as a whole is very simple in its construction and may be more quickly

operated to receive a quilt than other devices for performing this office now in use. 20

Having described our invention, we claim—

In a fabric-supporting device, the combination, with a rectangular frame, two of the opposite sides of which are longitudinally slotted, a bolt through each slot, a block upon 25 the inner end of the bolt, provided with a pocket, a clamping-tube extending between and resting within each of the oppositely-located pockets, and a series of clamps adjustably secured to said side pieces intermediate 30 the blocks, substantially as set forth.

REUBEN T. PALMER, JR.
FREDERIC W. MERCER.
